2,577,362

SWITCH PULL MECHANISM

Rudolf Popp, Valparaiso, Ind., assignor to McGill
Manufacturing Company, Inc., Valparaiso, Ind.,
a corporation of Indiana

Application November 2, 1946, Serial No. 707,413

2 Claims. (Cl. 74—501)

1

This invention relates to a switch mechanism and more particularly to a connector device for actuating a switch mechanism of the type in which a reciprocating motion is converted to rotary motion through the operation of a universal connection. Specifically, the present invention is an improvement on my prior Patents 1,974,054 and 2,378,655, both assigned to the same assignee as the present application.

Electric switches and switch mechanisms of the type disclosed in the above-mentioned patents are manufactured on a mass production basis. It will be apparent, therefore, that a substantial saving in manufacturing costs is accomplished whenever steps in the manufacturing process are eliminated. This is especially true if the steps eliminated involve complicated processes such as soldering processes, molding and forming operations, drilling, tapping and threading operations and the like. In such switch mechanisms, it is desirable that the parts thereof are so constructed as to provide very efficient operation, flexibility for mounting the mechanism in various fixtures with which they are usually associated, together with the reduced manufacturing cost referred to above by eliminating the requirement of costly parts.

Accordingly, it is an object of the present invention to provide a new and improved switch mechanism.

It is another object of the present invention to provide a switch mechanism with simple parts involving inexpensive manufacturing operations, which mechanism includes the desirable features of greater ease of assembly and more satisfactory operation.

It is still another object of the present invention to provide a universal connection which is comprised of very few parts having liberal manufacturing tolerances adapted to be positively assembled together with a minimum number of assembly operations.

It is a further object of the present invention to provide a new and improved switch mechanism in which costly assembly operations are completely eliminated and yet where the resultant switch mechanism is even more satisfactory in operation and efficiency than similar prior art devices.

It is a feature of the present invention to provide a universal connection in which a simple punching is employed to connect the reciprocating actuating member of the switch with a suitable beaded chain in a positive and foolproof manner.

2

It is another feature of the present invention to provide a new and improved switch mechanism in which expensive soldering operations are completely eliminated by employing an improved U-shaped frame and nipple arrangement associated with the universal connection having numerous advantages from the standpoint of mounting, operation, and the like.

Further objects and advantages of the present invention will become apparent as the following description proceeds and the features of novelty which characterize this invention will be pointed out with particularity in the claims annexed to and forming a part of this specification.

For a better understanding of the present invention, reference may be had to the accompanying drawing in which:

Fig. 1 is a perspective view of a switch mechanism embodying the present invention;

Fig. 2 is a plan view of the switch mechanism when mounted in a suitable housing, with the cover of the housing and an insulating plate of the switch removed to clarify the showing, the universal connection being illustrated in a switch actuating position;

Fig. 3 is a side view of the U-shaped frame employed in connection with the universal connection;

Fig. 4 is a side view of the threaded nipple employed with the U-shaped frame of Fig. 3;

Fig. 5 is an assembled view of the U-shaped frame and nipple shown in Figs. 3 and 4 of the drawing;

Fig. 6 is a longitudinal sectional view of the U-shaped frame and nipple of Fig. 5;

Fig. 7 is a perspective view of a stamping employed in the present invention to connect the reciprocating switch actuating member with the actuating chain;

Fig. 8 is a longitudinal sectional view through the universal connection of the switch of the present invention showing the relationship of the stamping of Fig. 7 to the reciprocating, actuating member and the chain;

Fig. 9 is an enlarged sectional view of a portion of Fig. 6, taken substantially on the line 9—9 in Fig. 12, showing assembly details of the U-shaped frame and associated nipple;

Fig. 10 is a sectional view taken on line 10—10 of Fig. 8;

Fig. 11 is an end view of the U-shaped frame of Fig. 3, looking from the left in Fig. 3; and

Fig. 12 is a transverse section on the line 12—12 in Fig. 5, looking in the direction of the arrows.

Referring now more particularly to the drawing, there is illustrated in Fig. 1 a switch mechanism 11 which is adapted to be mounted in a suitable housing, a portion of which is indicated at 12 in Fig. 2 which usually comprises a metal casing having an insulating liner or the like. The entire switch mechanism 11, including the casing 12, is adapted to be mounted in a suitable housing such as 13, a portion of which is shown in Fig. 2 of the drawing, in a manner which will be described in greater detail hereinafter. The housing 13 does not form a part of the switch mechanism but may form a part of a lamp or other electrical device with which the switch is to be associated. As illustrated in the drawing, the switch mechanism 11 comprises a pair of insulating plates or frame members 14 and 15. These plates are formed of any suitable insulating material but preferably one from which they may be stamped out of sheet material or the like. The plates 14 and 15 are spaced apart and held in position by a pair of conducting posts 16 and 17 which have portions 18 extending through the plates 14 and 15 which portions are upset or deformed at their extreme ends to effectively clamp the plates together and hold them in the position shown best in Fig. 1 of the drawing.

Attention now is directed particularly to Figs. 3, 4, 5, 6, 9, 11 and 12 of the drawing. In order further to rigidly relate the insulating plates 14 and 15 and to support the universal connection of the present invention, there is provided a U-shaped or bifurcated frame member 19 which is supported between the plates 14 and 15 and which also has projections 20 extending through these plates to hold the U-shaped member 19 in position. The manner in which the projections 20 are received in the plates 14 and 15 is indicated in Figs. 3 and 6. These projections 20 may also be upset or otherwise deformed to insure that the U-shaped member is held between the plates 14 and 15. Attached to U-shaped member 19 in an integral manner which will be described in greater detail hereinafter is a threaded nipple 21 upon which a lever generally indicated at 22, Figs. 1, 2 and 8, is adapted to rock when tension is applied to a flexible chain 23. The lever 22 is connected in accordance with the present invention as will be brought out hereinafter to a stem or reciprocating member 24 by a universal connection whereby the rocking of the lever 22 in any direction will pull the stem or reciprocating lever 24 to the right as viewed in Fig. 2 of the drawing through an opening. Stem 24 is provided with a head 25 and carries a U-shaped pawl 26 having parallel arms 27 and 28. Surrounding stem 24 is a helical spring 29 which in accordance with one feature of the present invention is positioned within a recess 30 in the nipple 21, while the other end of the spring rests against the pawl 26 normally holding the pawl and stem in the extended position shown by dotted lines in Fig. 2 of the drawing. The pawl 26 may be provided with a collar portion adjacent the point where the spring 29 engages the same for the purpose of centering the spring, the other end of the spring being centered by the recess 30 in the nipple 21.

As is clearly brought out in my prior Patent 1,974,054 referred to above, there is rotatably mounted between the insulating plates 14 and 15 a unitary contact bridging member generally indicated at 32, Fig. 2, having integral trunnions or stub shafts journaled in apertures in the plates 14 and 15. The bridging contact member

includes a large toothed wheel 33 provided with alternately deep and shallow teeth. The shallow teeth are provided with contacting faces 34, all of which are interconnected by a spider, not shown in the drawing, but fully disclosed in my above-mentioned patent. Adjacent the wheel 33 and integral therewith is a ratchet wheel 35 having teeth corresponding in number to the teeth in the larger wheel 33. The arms 27 and 28 of the pawl 26 straddle the ratchet gear 35 and the arm 27 is provided with a lateral projection 27A which engages behind the teeth of the ratchet wheel 35 to rotate the same upon reciprocal movement of the pawl 26.

Also in accordance with my prior Patent 1,974,054, each of the posts 16 and 17 mechanically supports and is electrically connected to a stationary contact member 38 formed of resilient material. These contact members 38 are so bent as is clearly indicated in Fig. 2 of the drawing as to have inwardly curved contacting portions lying opposite each other for engaging the movable contact bridging member and of a substantially straight portion which is re-bent upon itself to give additional resiliency. At the end of the re-bent portions the members are bent at a right angle and the right angled portion secured to the posts 16 and 17 in any suitable manner. When the stationary contact members 38 pass from the deep-cut insulating teeth of the bridging member 33 to the shallow contact carrying teeth, the drop is small and the tension of the springs is only slightly released, thus preventing rebound of the stationary contact members when they strike the contact bearing teeth. At one position of the movable contact member both of the stationary contact members will rest upon and be bridged by teeth having a conducting face in which position posts 16 and 17 will be electrically interconnected. Preferably each of the posts 16 and 17 carries a screw 40 by means of which conductors may be connected thereto so the switch may be associated with an electrical circuit which it is adapted to control. The particular construction of the stationary and movable contacts and the pawl for actuating the same forms no part of the present invention and is disclosed and described only to aid in better understanding the operation and arrangement of the features of the present invention relating to the universal connection and the support therefor.

One feature of the present invention is primarily concerned with the U-shaped member 19 and the nipple 21, together with the means for uniting these members into a unitary structure. In arrangements employed heretofore similar members were united by a soldering operation. A soldering operation is an expensive operation and in addition, involves extra plating and handling of the parts to neutralize the action of the soldering acid. In accordance with the present invention, the nipple 21 is provided with a substantial threaded portion clearly indicated in the drawing which threaded portion has a sufficient dimension that it will support a pair of nuts such as are indicated at 41 and 42 in Fig. 2 of the drawing for clamping the wall of the switch housing 13 or the like therebetween. In addition, the nipple 21 includes a sleeve or cylindrical extension 21A which is adapted to be inserted into an opening 19A in the base or bight 19B of the U-shaped member 19. By means of a swaging or clinching step, the sleeve-like extension 21A is deformed into arcuate lips as is

clearly shown at 21B in Figs. 9 and 12 of the drawing to integrally unite the nipple 21 and the U-shaped member 19 without the use of solder or any other means. Diametrically opposite portions 21C of the sleeve 21A (shown in Figs. 5, 6 and 12) are forced into pockets or recesses 19C which extend from the opening 19A into the legs of the bifurcated frame member 19. In this way the nipple 21 and frame member 19 are prevented from twisting relative to each other. The over-all length of the integrally united U-shaped member 19 and the nipple 21 as shown in Fig. 5 of the drawing is considerably less than or in event no greater than in prior arrangements by virtue of the fact that the nipple 21 is recessed for the spring as shown at 30. Consequently, even through a much longer threaded portion is provided on the nipple 21 than in prior arrangements, the switch embodying this arrangement is just as compact if not more so.

In accordance with the present invention, the diameter of the nipple 21 is substantially greater than that employed heretofore whereby the contour of the end upon which the lever 22 sets may be formed for most satisfactory operation. As is best shown in Fig. 6 of the drawing, a circumferential groove 43 is provided which has a substantial depth and which has the outer wall thereof formed parallel to the axis of the nipple 21 while the inner wall of the circumferential groove slopes at an angle of substantially 45 degrees as is clearly evident from Fig. 6 of the drawing. With this arrangement a much better seating action for the lever 22 as is shown in Figs. 2 and 8 of the drawing is provided. The end 22A of the lever 22 rests on the shoulder defined by the outer wall of the groove 43 while the 45 degree rise at the inner wall of the groove 43 indicated at 43A in Fig. 8 of the drawing insures the longest possible reciprocating movement of the stem or reciprocating lever 24 and consequently, the maximum movement of the pawl 26. It has been found that with the present arrangement, the movement of the pawl is increased by $\frac{1}{8}$ of an inch, thereby permitting much greater tolerances in the dimensions of the parts. The greater depth of the circumferential groove 43 prevents the lever 22 from slipping off the nipple 21 when being tilted as in Fig. 2 of the drawing. In prior art arrangements, if the construction was not exactly correct and usually a gauge was required to insure the proper arrangement of parts, there was slipping or rolling of the lower or pivoting edge of the lever 22. This is completely eliminated by the present arrangement.

As was pointed out above, the longer threaded portion on the nipple 21 permits the use of two separate nuts such as 41 and 42. It will be obvious from an examination of Fig. 2 of the drawing that the nut 41 prevents the mechanism of the switch from being pulled out of the housing since it engages the inside of the housing 13 and in fact, it prevents any force from being applied to the switch mechanism except through the pawl 26. The nuts 41 and 42 are very simple in construction and relatively inexpensive in contrast with the single nut employed in prior art devices which was usually required to have a countersunk portion to accommodate the frame member associated with the nipple which nipple in the prior art arrangements had a very short thread.

In accordance with a further feature of the present invention, there is provided a connector

45 for connecting the chain 23 with the reciprocating member or stem 24. This connector 45 is a simple stamping which is very inexpensive to manufacture and is much less complicated than the devices employed for this purpose heretofore which usually comprised a stamping which required several shaping or forming operations. As illustrated, the connector 45 includes a hook 47 at one end thereof for engaging the reciprocating member or stem 24 as is clearly shown in Fig. 8 of the drawing. The other end of the connector 45 is provided with an opening 48 of circular shape of a diameter sufficiently large to just encircle one bead or ball of a beaded chain 23 in the manner indicated in Fig. 8 of the drawing. The opening 48 is provided with a slot 49 through which the connecting portion of the beaded chain extends but which slot is sufficiently small to prevent the bead itself from passing therethrough.

At the edges of the connector 45 intermediate the hook 47 and the circular opening 48 are provided a pair of notches 50 which receive the embossed or dented-in portions 51 of the lever 22 (Figs. 8 and 10). It will be understood that the lever 22 might be provided with tapped openings for set screws which would engage the slots 50 in the connector 45. However, from the standpoint of ease of assembly and manufacturing cost, the embossed portions 51 are preferred. Since the connector 45 has a substantial thickness, the swaging or indentation of the lever 22 at points 51 provides a sort of flat surface indicated at 52 in Fig. 10 of the drawing thereby preventing twisting of the connector 45 relative to the lever 22 which is very desirable.

An examination of Fig. 8 of the drawing indicates clearly that the bead on the beaded chain 23 disposed in the opening 48 is firmly held therein by the shoulders adjacent the aperture 49. In addition, a considerable saving in beaded chain is provided by the present arrangement since in the prior art arrangements usually a series of beads such as three or more were required to make the connection which in the present arrangement requires a single bead. When one considers the manufacture of these switches by the hundreds of thousands this amounts to a considerable saving.

The contour of the lever 22 is such as to readily provide for the proper seating of an extension arm of the type such as disclosed in Klous Patent No. 1,670,453 granted May 22, 1928.

In view of the detailed discussion included above, the operation of the switch mechanism embodying the present mechanism will be apparent and no further discussion thereof will be included herein. It will be seen that there has been provided a switch mechanism which is considerably less expensive to manufacture since it eliminates certain expensive steps employed in the manufacture of similar mechanisms heretofore. Furthermore, the mechanism is constructed so as to provide efficient operation thereof further characterized by the fact that it is arranged for great flexibility from the standpoint of mounting in various wall fixtures and the like.

While there has been described a particular embodiment of the present invention, it will be obvious to those skilled in the art that various changes and modifications may be made without departing from the present invention, and it is aimed in the appended claims to cover all such changes and modifications as fall within the true spirit and scope of the present invention.

I claim:

1. An electric switch pull chain unit adapted for universal-seated movement and having therein an actuating member with a looped connecting portion and a flexible chain of beads, the combination including a connector member for connecting said actuating member and said chain comprising a flat metal punching having at one end a body portion with an elongated recess therein and an opening at the inside end of the recess to provide a hook-like configuration in said body portion to permit the insertion of the looped connecting portion of the actuating member in the opening to the recess in a hooking-assembly operation and provide a hooked connection between the actuating member and the connector member, and said flat punching having a body portion at the other end thereof adapted to receive therein a bead from the chain, and said unit also including a tubular lever housing having an internal cavity shaped to receive the greater portion of the connector member therein, surrounding said connector member, and having an indented portion therein lockingly engaging the connector member within the housing.

2. An electric switch pull chain unit adapted for universal-seated movement and having therein an actuating member with a looped connecting portion and a flexible chain of beads, the combination including a connector member for connecting said actuating member and said chain comprising a flat punching having at one end a body portion with a deep recess therein and an opening at the inside end of the recess to provide a hook-like configuration of that said body

portion to permit the insertion of the actuating member in the opening in a hooking-assembly operation, said flat punching having at the other end a body portion with an aperture therein for receiving and carrying therein a bead in the chain, and said flat punching having two oppositely disposed indented edge portions intermediate the two body portions, and said unit also including a tubular lever housing surrounding said connector member and having indented portions therein lockingly engaging the connector member within the housing at the indented edge portions thereof.
